RADIO TRANSMITTER AMPLIFIER.

Donald L. Hings, Ottawa, Ontario, Canada, assignor to Electronic Laboratories, Inc., Indianapolis, Ind., a corporation of Indiana

Application August 8, 1942, Serial No. 454,083
In Canada August 6, 1942

2 Claims. (CL. 250—17)

1

My invention relates in general to a radio amplifier for supplying power to a load circuit and more specifically to a radio amplifier having an expansion control circuit arranged to increase the power supplied to the load circuit during modulation.

An object of my invention is the provision of a radio amplifier arranged to be connected between a load circuit and a terminal energized by a source of modulated radio frequency wherein the radio amplifier is arranged to increase the power supplied to the load circuit during modulation.

Another object of my invention is the provision of a radio amplifier having an amplifying circuit and an expansion control circuit, wherein both circuits are connected to a source of modulated radio frequency.

Another object of my invention is the provision of connecting both the amplifying circuit and the expansion control circuit to the source of modulated radio frequency through a tuned resonant circuit.

Another object of my invention is the provision of substantially matching the impedance of the amplifying circuit of my radio amplifier to the impedance of the source of modulated radio frequency.

Another object of my invention is the provision of matching the impedance of the expansion control circuit as well as the impedance of the amplifying circuit to the impedance of the source of modulated radio frequency.

Another object of my invention is the provision of connecting my radio amplifier to the source of modulated radio frequency through means of a common conductor having two branch circuits, wherein the amplified circuit is connected to one of the branches and wherein the expansion control circuit is connected to the other branch.

Another object of my invention is the provision of connecting the two branches to the common conductor through a tuned resonant circuit.

Another object of my invention is the provision of a radio amplifier which will automatically work either from a source of modulated radio frequency or from a source of unmodulated radio frequency; in the latter case the expansion control circuit remaining inactive.

Other objects and a fuller understanding of my invention may be had by referring to the following description and claims, taken in conjunction with the accompanying drawings, in which—

Figure 1 shows the manner in which my radio

amplifier may be connected to a source of modulated radio frequency, wherein the output of the radio amplifier is arranged to energize the antenna load circuit;

Figure 2 illustrates diagrammatically a radio amplifier embodying the features of my invention;

Figure 3 is a wave representation of the carrier and the modulated radio frequency without the power expansion;

Figure 4 is a view which is shown in comparison with Figure 3 illustrating the carrier wave and the modulated radio frequency wave with expanded power.

15 With reference to Figure 1 of the drawing, my radio amplifier is designated generally by the reference character 11 and is arranged to have its input connected to a source of modulated radio frequency which is illustrated generally by the reference character 10. The output of the radio amplifier 11 is arranged to supply energy to an antenna 12. There are many applications to-day where it is desirable to increase the power delivered to an antenna or other load circuit from

20 the existing equipment. An illustration of existing equipment would be where the antenna 12 was directly connected by the antenna cable 18 and the connecting plug 20 to the output terminal 13 of the source of modulated radio frequency 10.

25 With my invention I disconnect the antenna from the output terminal 13 of the source of modulated radio frequency and connect the input of my radio amplifier 11 to the output terminal 13 and then connect the antenna 12 to the amplifier output terminal 19, so as to deliver increased power to the antenna. As shown in Figure 1, the input terminal 14 of my radio amplifier 11 may be connected to the output terminal 13 of the source of modulated radio frequency by

30 a cable 17 having a connecting plug 15 on the lefthand end thereof to fit into the output terminal 13 and having a connecting plug 16 upon the righthand end thereof to fit into the input terminal 14. The cable 17 may be shielded so that a common ground through the housings of both of the units may be provided. In other words the shielding of the cable is arranged to keep the housings of the two units at a common potential, although other connections may be provided for

35 this purpose. In the event it becomes desirable to increase the power delivered to the antenna 12 from the source of modulated radio frequency 10 it is only necessary to insert my radio amplifier in the circuit as shown in Figure 1 for delivering the increased amount of power to

40

45

55

the antenna. My radio amplifier may also be used to amplify the power to any type of load circuit as well as the antenna as illustrated.

In Figure 2 I illustrate diagrammatically the circuit arrangement of my radio amplifier and comprises generally a radio frequency amplifier circuit illustrated generally by the reference character 24 and an expansion control circuit indicated by the reference character 25. The radio frequency amplifier circuit includes an amplifying tube 26 which is connected to the input terminal 14 through a tuned coupler illustrated generally by the reference character 27. The output circuit for the amplifier tube 26 is connected to the output terminal 19 through an output antenna coupler illustrated by the reference character 28.

The amplifier tube 26 may be of any suitable type and I find from practice that a beam type tube works very satisfactorily. The beam forming plates of the tube are illustrated by the reference character 32 and are connected to ground. The cathode 29 of the tube is heated from a filament supply indicated generally by the reference character 37. The control grid 30 is connected to the tuned coupler 27 and the plate 33 is connected to the output antenna coupler 28 through a blocking condenser 34. The screen grid 31 is bypassed to ground through a by-pass condenser 42, and is supplied with energy from a screen supply 43. The plate voltage for the amplifier tube 26 is supplied from a plate supply indicated generally by the reference character 40 through a radio frequency choke 41. The output antenna coupler 28 which couples the plate 33 to the output terminal 19 and the antenna 12 comprises a tuning inductance 35 and tuning condenser 36 which is connected to ground.

The control grid 30 of the amplifier tube 26 is biased with respect to the cathode 29 from a bias supply indicated generally by the reference character 78 through a resistor 77 and the coupler inductance 44 of the tuned coupler 27. The operation of the amplifier tube 26 is controlled by the control grid 30 for supplying amplified power to the antenna 12. The tuned coupler 27 which comprises the inductance 44 and the variable condenser 45 may be tuned to resonance so that the maximum voltage may be applied to the grid 30. The inductance 44 is provided with a variable tap 48 which is connected to the common conductor 47 that leads to the input terminal 14. Accordingly, with this arrangement the impedance of the source of modulated radio frequency 10 may be matched by adjustably setting the tap 48.

The description up to the present time dealt with the radio frequency amplifier circuit 24. I will next describe the arrangement of the expansion control circuit designated generally by the reference character 25 which comprises a rectifier-amplifier tube 50 and a bias control tube 51. The rectifier-amplifier tube 50 may be a dual purpose tube in which the cathode 53 and the plate 54 constitute a diode and in which the cathode 53, the plate 55 and the control grid 56 constitute a triode. The cathode 53 may be heated by a heater filament 52 which is supplied with energy from a filament supply 74. The diode plate 54 is coupled to the adjustable tap 49 on the coupler inductance 44 through a condenser 57. The plate 54 and the cathode 53 operate as a rectifier or detector and function to establish a voltage across the load resistance 59 which is proportional to the voltage of the

source of modulated radio frequency 10. The radio frequency current is prevented from flowing in the diode load resistance 59 by means of a radio frequency choke 58. The voltage which appears across the diode load resistance 59 is proportional to the modulation and is impressed upon the control grid 56 through a coupling condenser 62. In this manner, the amplified output of the rectifier-amplifier tube is proportional to the modulation. The cathode 53 is maintained at a positive bias by means of a cathode resistance 61 which is by-passed to ground through a cathode by-pass condenser 60. The control grid 56 is connected to ground through a grid resistor 63. The amplified output of the rectifier-amplifier tube 50 is fed into the bias control tube 51 through a coupling transformer 64. The voltage of the triode plate 55 is supplied by the plate supply 79 through the primary winding of the transformer 64. The bias control tube 51 comprises a cathode 69, two control grids 70 and 72, and two plates 71 and 73 connected in parallel to ground. The cathode 69 may be heated by a heater filament 68 supplied with energy from the filament supply 74. The control grids 70 and 72 are connected respectively to the two ends of the secondary winding of the coupling transformer 64. A bias battery 75 is connected to the center tap of the secondary winding so that the control grids 70 and 72 will be maintained at a sufficiently high bias to prevent any current from flowing from the cathode 69 to the plates 71 and 73 when no modulated energy is being received by the transformer 64 from the tube 50. When amplified modulated energy is being received by the transformer 64 from the tube 50, the bias control tube 51 operates to pass current from the bias supply 78 through the resistor 77, the cathode 69 and the plates 71 and 73. The flow of current through the resistor 77 causes a voltage drop thereacross which in turn reduces the negative bias of the control grid 30 of the amplifier tube 26. The reduction in the negative bias of the control grid 30 causes the amplifier tube 26 to deliver more power to the antenna 12 during modulation. The tube 51 passes current for both the negative and positive peaks of the modulated waves, and this action when taken in combination with the condenser 76 produces an integrated effect to give a smooth performance relative to changing the bias on the grid 30 of the amplifier tube 26 to cause the tube to deliver an increased amount of power to the antenna during modulation. Thus with reference to Figure 4, the dotted line 80 illustrates diagrammatically the smooth and integrated expansion of the carrier, as affected by the combined action of the bias control tube 51, the resistor 77 and the integrating condenser 76. The expanded carrier occurs only during modulation and enables more power to be supplied to the antenna 12 for this period of time, when power is mostly needed. Figure 3 illustrates the carrier wave and the modulated wave when there is no power expansion, wherein the dotted line 81 represents the fact that the carrier is not expanded during modulation. My radio amplifier will automatically work either from a source of modulated radio frequency as described above to give expanded power during modulation or from a source of unmodulated radio frequency such as a code signal, in the latter case the expansion control circuit 25 remaining inactive.

It is to be observed that the radio frequency amplifier circuit 24 and the expansion control

circuit 25 are connected to the common conductor 47 by two branch circuits respectively through the tuned coupler 27. With this arrangement it is only necessary to have a single cable inner-connecting the source of modulated radio frequency 10 and my radio amplifier 11. As before explained, the common ground connection for the source of modulated radio frequency 10 and my radio amplifier 11 may be taken care of by a shield on the cable 17. Therefore my invention makes possible a quick change over from a source of low power supply to the antenna to a source of high power supply resulting from an expanded carrier to the antenna, without any special connections and without breaking into the housing which encloses the source of modulated radio frequency. Furthermore my radio amplifier may be connected to any source of modulated radio frequency regardless of the impedance thereof since I am able to match the impedance through the adjustable taps 48 and 49 on the coupler inductance 44.

The amplifying tube 26 functions as an amplifier for all types of energies supplied to it by the source 10, but in addition functions to give an expanded carrier during modulation, so that an increased amount of amplified power may be delivered during modulation over that delivered during an unmodulated wave. That is to say, the amplifying 26 is rendered more sensitive during modulation with the result that more power is delivered to the antenna, or other output load, for an equivalent signal input during an unmodulated wave. Although I have shown and described my invention with a certain degree of particularity, it is understood that changes may be made therein without departing from the spirit of the invention which are included in the scope of claims hereinafter set forth.

I claim as my invention:

1. The combination with a housing having a source of modulated radio frequency therein and a terminal extending through the housing for conducting the source of modulated radio frequency to the outside of the housing, and a radio frequency wave emitting load circuit arranged to be connected to said terminal, of a radio amplifier comprising a radio frequency amplifier circuit having an input and an output, means for disconnecting said load circuit from said terminal

and connecting same to said output, a feed line shielded from the emitting load circuit for connecting said input to said terminal, an expansion control circuit energized from said terminal and arranged to increase the power supplied by said radio frequency amplifier circuit during modulation, and a common ground circuit for the source of modulated radio frequency and for the radio amplifier.

- 10 2. The combination with a housing having a source of modulated radio frequency therein and a terminal extending through the housing for conducting the source of modulated radio frequency to the outside of the housing, and a radio frequency wave emitting load circuit arranged to be connected to said terminal, of a radio amplifier comprising a radio frequency amplifier circuit having an input and an output, means for disconnecting said load circuit from said terminal and connecting same to said output, a feed line shielded from the emitting load circuit for connecting said input to said terminal, an expansion control circuit energized from said terminal and arranged to increase the power supplied by said radio frequency amplifier circuit during modulation, said source of modulated radio frequency being grounded to said housing, and connection means for grounding the radio amplifier to said housing.
